By Charles J. Schmidt
Atty.

UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

SOLDERING IRON.

Application filed February 15, 1924. Serial No. 693,028.

To all whom it may concern:

Be it known that I, WILLIAM J. FRISBIE, a citizen of the United States, and a resident of Chicago, in the county of Cook and

5 State of Illinois, have invented certain new and useful Improvements in Soldering Irons, of which the following is a specification.

10 My invention relates to soldering irons particularly to that type in which expanding heated fuel vapor will generate its own pressure for keeping a substantial flame playing around the soldering tip. The object of the invention is to provide improved 15 construction and control for permitting all alcohol or hydrocarbon fuel to be used with equal efficiency.

My improved device is shown on the accompanying drawing, in which

20 Fig. 1 is a side elevational view,

Fig. 2 is a vertical diametral sectional view, and

Fig. 3 is a sectional view on line 3—3, Fig. 1.

25 In general the iron comprises a handle part which is hollow to afford a reservoir for the fuel, and above the handle is the generator and burner structure. The handle structure comprises the body part 10 and the base 11 having threaded detachable engagement therewith. The body and base are of wood or other heat insulating material and the base is sufficiently flared at its lower end to provide ample seating surface for 30 holding the iron in upright position. The axial bore of the handle body part receives the metallic tube 12 to which it is rigidly secured by means of a set screw 13. Secured in the lower end of the tube is the internally threaded bushing 14 for receiving the filler plug 15. The bushing has the annular conical seat 16 to be engaged by the annular washer 17 imbedded in the plug so that a tight joint will result and leakage 35 will be prevented, the washer being of some yielding material such as lead or copper.

The upper end of the tube 12 is reenforced by the encircling metal band 18 and threaded into the upper end of the tube is the lower part 19 of the valve fitting receiving head 20. The joint between the flange and tube is preferably thoroughly sealed by means of litharge or other suitable material which will resist heat.

50 The body 21 of the valve fitting V seats

on the head 20 and has the threaded end 22 engaging in the head. The body has the chamber 23 therein which communicates with the upper end of the tube space.

Above the chamber 23 the valve body has the lateral extension 24 having the axial bore 25 which intermediate its ends is internally threaded to receive the threaded section of the valve stem 26 as shown in Fig. 2. The cap 27 receives the outer end of the extension 24 and serves to force packing material 28 around the stem to prevent leakage. The outer end of the valve stem is deflected and supports the handle 29. The inner end of the bore 25 is contracted and provides a conical valve seat 30 for receiving the conical valve end 31 of the stem when the stem is in its inner position. The end of the bore is connected by the duct 32 with the upper end of the chamber 23. Outside of the valve seat the valve bore is connected by the duct 33 with the socket 34 in which seats the burner tip 35.

Extending through the tube 12 is the wick 36 preferably of asbestos and it may be of braided formation as shown. At its upper end the wick extends into the chamber 23 and is preferably fluffed in the chamber to be more porous and to provide space for the expansion of the heating fuel and vapor. Within the space enclosed by the flange 19 on the head 20 I insert packing material 37 preferably of asbestos and below this packing I insert a series of washers 38 preferably of felt, these washers surrounding the wick 36 and being supported between the flange 19 and the annular shoulder 39 provided on the tube 12. The chamber 23 serves as a generating chamber for converting liquid fuel into vapor and for heating the vapor to gaseous condition. The chamber is surrounded by the sheet metal priming cup 40 which is securely held by being clamped between the head 20 and the base of the valve structure body part 41.

The upper end of the valve structure body is threaded and has the seating shoulders 42 for the lower end of the Bunsen burner tube 43. This tube has the air apertures 44 adjacent the tip 35 and above these openings are other air apertures 45. The upper end of the Bunsen tube is threaded to receive the threaded lug 46 on the soldering tip 47. Below the tip are the flame outlet openings 48, and the base of the tip and

its lug are preferably cut away at opposite sides to leave the passageways 49 and 50 for the flame, the rounded surfaces 51 causing the flame to curl around the tip to rapidly 5 and efficiently heat it.

To charge the iron with fuel, the base 11 is removed and the iron inverted, and after the plug 15 is withdrawn the fuel can be poured into the reservoir provided by the 10 tube 12. The plug and base are then re-applied and the iron supported in vertical position on its base. The fuel may be either alcohol or the like, or a hydrocarbon liquid. A portion of the fuel is poured into the 15 priming cup 40 and ignited and the flames of this burning fuel will rapidly heat the valve fitting and the generating chamber 23 so that fuel which has been conducted into said chamber along the wick will be 20 rapidly vaporized and the vapor highly heated and gasified. The valve stem is then rotated to unseat its end from the valve seat 30, and the generated gas will then flow through the duct 32, the valve bore, 25 and the duct 33 and into the tip socket 34, from where it travels thru the bore of the tip and emerges from the tip orifice into the burner tube where it is immediately mixed with air entering through the apertures 44, and later with air entering through 30 the apertures 45. The valve is opened while there is still some priming fluid burning so that the flame can ignite the gas issuing from the tip. As there is considerable 35 expansion when the fuel is vaporized and the vapor gasified, corresponding pressure will be generated and this pressure will force the gas from the burner tip, the flow being of course controlled by the valve. 40 The flame will impinge against the soldering tip and if the pressure is great enough the flame will also extend through the apertures 48 and the passageways 49 and 50. If it is desired to use the iron as a torch, 45 the soldering tip is unscrewed so that the flame can shoot out of the end of the Bunsen tube.

During use as a torch or for soldering purposes the iron is usually held in inclined 50 or inverted position, and the liquid fuel will therefore have a tendency to flow more rapidly toward the generating chamber, and might cool the chamber sufficiently to prevent further generation. In order to retard the travel of the liquid the washers 55 38 referred to are inserted. These washers surround the asbestos wick and are of felt or other suitable material through which the fuel can flow only slowly. The flow 60 of the fuel toward the generating chamber is therefore confined practically to the more porous asbestos wick. The asbestos packing 37 below the valve structure supporting head 20 serves to check the flow of heat 65 toward the handle, any heat traveling down

the head 20 will be absorbed by this packing and also by the wick and surrounding felt washers and will be utilized in preliminarily heating the fuel. To assist in supporting the felt washers a perforated 70 plate or screen 52 is interposed between the bottom washer and the annular shoulder 39. A screen 53 is preferably inserted near the top of the generating chamber 23 above the asbestos wicking therein to prevent 75 escape of any wick parts or solid particles into the bore 32. Filter material 54 may also be provided in the tip socket 34 in advance of the burner tip to protect the fine tip orifice and prevent clogging thereof 80 by any solid particles which might reach the tip socket. After the iron has been primed and is burning the heat will be conducted downwardly by the valve fitting metal to the generating chamber 23 and generation will be maintained. By adjusting the valve, the volume of flame can be controlled as desired.

I thus produce a simple yet efficient device which can be used as a torch or as a 90 soldering iron and in which alcohol or hydrocarbon fuel can be used with equal efficiency.

I do not desire to be limited to the exact construction and arrangement shown and described as modifications are possible which would still come within the scope of the invention.

I claim as follows:

1. In a device of the class described, the combination of a hollow handle structure forming a reservoir for fuel, a valve fitting above and communicating with said reservoir, said valve fitting having a generating chamber, an asbestos wick extending through 100 said reservoir and into said generating chamber, felt washers in the upper end of said reservoir surrounding said wick, a gas tip at the upper end of said valve fitting and a passageway connecting said generating 105 chamber with said tip, and means for controlling the flow through said passageway.

2. In a device of the class described, the combination of a handle having a bore forming a reservoir, a valve fitting above 110 and communicating with said reservoir, said valve fitting having a generating chamber therein above the upper end of said reservoir, an asbestos wick extending through 115 said reservoir and into said generating chamber, felt washers at the upper end of said reservoir surrounding said wick, a gas outlet tip at the upper end of said valve fitting, said valve fitting having a passageway connecting said generating chamber with 120 said tip, and a priming cup surrounding said generating chamber.

3. In a device of the class described, the combination of a cylindrical tube forming 125 a reservoir, a bushing secured in the upper 130

end of said tube, a valve fitting on said bushing having a generating chamber there-in communicating with the upper end of said reservoir, a wick extending through said reservoir and into said generating chamber, asbestos within said bushing sur-rounding said wick, a tier of felt washers in the upper end of said reservoir below said asbestos packing and surrounding said wick, a gas outlet tip at the upper end of said fitting, said fitting having a passageway connecting said tip with said generating chamber, a valve for controlling said passageway, and a priming cup secured be-tween said fitting and bushing and sur-rounding said generating chamber.

4. In a device of the class described, the combination of a metal tube forming a reser-voir, a bushing secured in the upper end

of said tube, a fitting detachably engaging 20 said bushing, said fitting having a gener-ating chamber above said reservoir, an as-bestos wick extending through said reser-voir and into said generating chamber, as-bestos packing in said bushing surround-ing 25 said wick, a tier of felt washers below said packing and receiving said wick, said tube having an annular shoulder for supporting said washers, said fitting having a gas ori-fice at the upper end and a passageway con-necting it with said reservoir, and a prim-ing cup detachably secured between said fit-ting and bushing and surrounding said gen-erating chamber.

In witness whereof, I hereunto subscribe 35 my name this 9th day of February A. D., 1924.

WILLIAM J. FRISBIE.
